(57) **CLAIM**

The ornamental design for a bandage, as shown and described.

DESCRIPTION

FIG. 1 is a front perspective view of our new design.

FIG. 2 is a front view thereof.

FIG. 3 is a rear view thereof.

FIG. 4 is a right-side view thereof.

FIG. 5 is a left-side view thereof.

FIG. 6 is a top view thereof; and,

FIG. 7 is a bottom view thereof.

The broken lines showing the remaining portions of the bandage are for environmental purposes only and form no part of the claim.
